UNITED STATES PATENT OFFICE.

HARVEY F. CRAWFORD, OF BROCKTON, MASSACHUSETTS.

MEDICINAL BOOT OR SHOE.

SPECIFICATION forming part of Letters Patent No. 662,223, dated November 20, 1900.

Application filed July 9, 1900. Serial No. 22,926. (No model.)

To all whom it may concern:

Be it known that I, HARVEY F. CRAWFORD, a citizen of the United States, residing at Brockton, in the county of Plymouth and State of Massachusetts, have invented certain new and useful Improvements in Medicinal Boots or Shoes, of which the following is a specification, reference being had therein to the accompanying drawings.

10 Figure 1 is a top plan view of a shoe constructed in accordance with my invention, the upper being removed for greater clearness. Fig. 2 is a central lengthwise section on line 22 of Fig. 1. Fig. 3 shows a modification.

15 The object of my invention is to provide boots, shoes, slippers, and the like with sanative or medicinal means which may operate through the feet of the wearer; and my invention, broadly stated, consists in the combination of a chambered heel provided with a medicinal "battery," as I term it, that is in effective communication with the insole as the medicine-distributing factor of the combination.

25 In the drawings illustrating the principle of my invention and the best mode now known to me of applying that principle, *a* is the heel, and *b* the outersole, of a shoe. Heel *a* is formed with a recess *a'*, which extends from the top 30 of the heel part way down to the bottom thereof. Recess *a'* forms a receptacle to hold the "battery" *d*, by which I mean any mass or device possessed of curative or exercising sanitary or health-benefiting qualities—such, 35 for example, as a medicated mass which, or the vapors or proximity or effect of which, would benefit the wearer by being brought into contact with or into proximity to his feet, or such as a voltaic battery with proper leads, 40 as hereinafter mentioned.

The heel portion of insole *b'* is preferably perforated at *b²* to correspond to the recess *a'* and permit the ready insertion and removal of the battery, which may be covered, if desired, by the usual sock-lining, but which is 45 shown covered by a special cover. The insole is suitably perforated at *b⁴*, &c., forward of the heel portion, the perforations *b⁴* being connected with the battery by means of conductors *b⁵*, these conductors being either channels through which the contents of the battery 50 may pass to the perforations *b⁴* or wires

through which currents from a voltaic battery may pass. I here use the term "conductor" in its broadest sense, meaning thereby an effective means of communication between the battery in the heel and the perforations through the insole forwardly of the heel, at which perforations the bottom of the wearer's foot is brought into proximity with the contents of or sanative force or influence in the perforations *b⁴*, whatever such contents may be.

In Figs. 1 and 2, illustrating one form of my invention, the battery *d* in the recess or receptacle *a'* in the heel is made up of alternating disks of zinc *z* and copper *c*, the copper or positive plate forming the outermost element of the pile. The lowermost zinc element *z* is connected by an electrical conductor *z'* with zinc electrodes *z²* in certain of the perforations *b⁴*, and the uppermost copper element of the pile is connected by wire *c'* with copper electrodes *c²* in other of the perforations *b⁴*. In addition to these elements 75 the receptacle *a'* is provided with any suitable energizing material, such as acetic acid or the like, and when the shoe is in use the foot of the wearer contacting with the electrodes *c²* and *z²* completes the circuit. If desired, the opening of receptacle *a'* may be provided with a cover *a²* of any suitable construction, shown in this case as one which screws into the opening of the receptacle. The walls of the recess will ordinarily absorb 85 more or less of the acidulous agent, remain moist, and keep the plates in condition for electrical action.

In the modification shown in Fig. 3 the battery *d* is a medicinal mass which extends 90 through the conductor-channels and into the perforations *b⁴*. As an example of what such a medicated mass may be I will mention as one of the numerous examples a salicylic-acid ointment.

95 The advantage of my invention is that a very considerable battery of any desired kind may be readily carried in the recessed heel and brought into communication with the bottom of the wearer's feet, so that medication 100 may be effected by galvanic currents or by absorption of proper medicaments.

What I claim is—

1. In a boot or shoe, the combination of a

heel having a recess which extends from the upper surface of the heel part way down to the bottom thereof, with an insole perforated forwardly of said recessed heel, and a battery 5 mounted in said recess and operatively connected with said perforations.

2. In a boot or shoe, the combination of a heel having a recess which extends from the upper surface of the heel part way down to 10 the bottom thereof, and a cover for the opening of said recess.

3. In a boot or shoe, the combination of a heel having a recess which extends from the upper surface of the heel part way down to 15 the bottom thereof; an insole perforated forwardly of the heel; positive and negative electrodes in said perforations; a voltaic battery in said recess and leads connecting a positive element of the battery with a positive

electrode in the insole; and connecting a negative element of the battery with a negative electrode in the insole. 20

4. In a boot or shoe, the combination of a heel having a recess which extends from the upper surface of the heel part way down to 25 the bottom thereof; with an insole having a perforation in its heel part above the opening of said recess.

5. The combination in a boot or shoe of a heel having a recess which extends from its 30 upper portion part way to its bottom with a sanative battery in said recess.

In testimony whereof I affix my signature in presence of two witnesses.

HARVEY F. CRAWFORD.
